(57) **CLAIM**

The ornamental design for a scarf, as shown and described.

DESCRIPTION

FIG. 1 is a top, front, right side perspective view of a scarf showing a first embodiment of our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, front, right side perspective view showing a second embodiment thereof;

FIG. 9 is a front elevation view of FIG. 8;

FIG. 10 is a rear elevation view of FIG. 8;

FIG. 11 is a left side elevation view of FIG. 8;

FIG. 12 is a right side elevation view of FIG. 8;

FIG. 13 is a top plan view of FIG. 8; and,

FIG. 14 is a bottom plan view of FIG. 8.

The dash-dash broken lines show portions of the scarf that form no part of the claimed design. The dot-dash broken lines show boundaries of the claimed design and form no part of the claimed design. The pairs of adjacent bracketed wavy break lines shown in FIGS. 8-10, and 13-14 form no part of the claimed design and indicate that the appearance of any portion of the article between the break lines forms no part of the claimed design.
